THERMOSTATIC VALVE

Franklyn Y. Carter, Dearborn, Mich., assignor to
Detroit Lubricator Company, Detroit, Mich., a
corporation of Michigan

Application April 30, 1948, Serial No. 24,189

7 Claims. (Cl. 236—93)

1

This invention relates to new and useful improvements in thermostatic valves and more particularly to valves for relieving dangerously high pressures resulting from high temperatures in fluid containers such as receivers in refrigeration systems or for draining excess hot water from a domestic hot water tank.

One of the objects of this invention is to provide a new and improved thermostatically operated valve.

Another object is to provide a thermostatically operated safety valve which will open very slowly until a predetermined temperature is reached and then will open rapidly upon rise in temperature within a predetermined range and will close rapidly upon fall of temperature within said range.

Another object is to provide an improved valve for relieving excessive pressure in a refrigerant receiver resulting from excessive temperature.

Another object is to provide an improved valve for automatically draining water from a domestic hot water tank upon excessive rise in temperature therein.

Another object is to provide a thermostatically operated mechanism which will not have operative movement until a predetermined temperature is reached and then will move through its entire range of operative movement rapidly and within a small predetermined range of temperature.

Other objects will become apparent from time to time throughout the specification and claims as hereinafter related.

This invention comprises the new and improved construction and combination of parts, to be described more fully hereinafter, and the novelty of which will be particularly pointed out and distinctly claimed.

In the accompanying drawings, to be taken as a part of this specification, there are clearly and fully illustrated two preferred embodiments of this invention, in which drawings:

Figure 1 is a view in vertical cross-section of a valve embodying this invention and particularly adapted for relief of excessive pressure in a refrigerant receiver.

Fig. 2 is a view in vertical cross-section of a valve embodying this invention and particularly adapted for draining excess hot water from a domestic water heating tank, and

Fig. 3 is a graph illustrating the change in expansion of the thermo-responsive material used in the power element with change of temperature.

Referring to the drawings by characters of

2

reference, there is shown in Fig. 1 a segment of a casing 1 of a liquid refrigerant receiver and having an internally screw-threaded fitting 2 thereon. Screw-threadedly secured in the fitting 5 2 there is a plug member 3 having a central passageway 4 extending longitudinally therethrough and having an internal partition 5 dividing the passageway 4 into two sections 6 and 7. There is an aperture 8 in the partition 5 which provides a valve port. A valve member 9 which is positioned externally of the port 8 is cooperable therewith to control fluid flow through the passageway 4. The valve member 9 is carried by a valve stem 10 which extends through the valve port 8 into the passageway portion 7 and is adjustably screw-threadedly secured in an actuating piston 11. There is a power element structure 12 comprising a tubular guide member having a cup-shaped member 13 screw-threadedly secured in the passageway portion 7 and having a hollow cylindrical projecting portion 14 extending from the base thereof. There are provided in the base of the cup-shaped member 13 one or more apertures 15 which permit fluid flow to the valve port 8. The cylindrical projecting portion 14 has an annular flange 16 around its end portion and is provided with a passageway or bore extending longitudinally therethrough. There is a cup-shaped power element 17 which is secured to the flange 16 by an inturned flange portion 18 and which closes the bore of the projecting portion 14. There is a flexible resilient diaphragm 19 which extends across the open end of the power element 17 and which is secured at its edge portion between the power element 17 and the flange portion 16. Enclosed between the power element 17 and the diaphragm 19 there is a thermo-expansive material 20 which has a low rate of expansion at temperatures both below and above a predetermined temperature range and has a high rate of expansion within the predetermined temperature range. This material is preferably a wax or mixture of waxes (or other organic solids) having a high rate of expansion when passing through a change of state and containing a high percentage (around 75-80%) of a finely divided heat transfer material such as powdered copper held in suspension by a viscous binder material such as polyisobutylene ("Vistanex"). The use of thermostatic material of this type is taught in Patent 2,259,846 to Vernet. If reference be had to Fig. 3, it is seen that in the 10° range of temperature from 205° F. to 215° F. there is an expansion sufficient to move the piston .120". The rate of expansion with

temperature may be varied according to the composition of material used in the power element and such compositions are disclosed and taught in the aforementioned patent to Vernet. The piston 11 which is adjustably secured to the valve stem 10 is slidably positioned in the bore of the projecting portion 14. There is provided within the bore of the projecting member 14 and abutting the diaphragm 19 a compressible and elastic plug member 21 which is operable to transmit movement from the diaphragm 19. Also within the bore of the member 14 there is an operating piston 22 having a projection 23 extending toward and normally having a clearance from the piston 11. The pistons 11 and 22 together comprise a plunger or thrust member. There is a helical lost-motion spring 24 which surrounds the projection 23 and which is compressed between the pistons 11 and 22. The piston 11 has a flange 25 about its outer end portion and there is provided a spring 26 which is compressibly positioned between the flange 25 and the partition 5.

In operation this valve functions as follows:

The spring 26 normally urges the valve member 9 toward closed position and is of sufficient strength to resist movement of the valve member 9 by the power element 17 at temperatures below the predetermined temperature range at which the thermo-expansive material 20 begins its change of state and increased rate of expansion. At lower temperatures as the temperature of the power element is increased the expansion of the thermo-expansive material 20 is transmitted through the plug member 21 to the piston 22. The clearance between the piston projection 23 and the piston 11 corresponds to the amount of expansion of the material 20 at lower temperatures. This motion of the piston 22 is taken up by the lost-motion spring 24 so that there is no movement of the piston 11 until the temperature is reached at which the material 20 begins to go through its change of state. When a predetermined temperature is reached, for example, at the point which the thermo-expansive material 20 begins to go through a change of state the piston projection 23 has engaged the piston 11 and the increased rate of expansion will cause the pistons 11 and 22 to be moved rapidly within a small range of temperature thus moving the valve to a full open position to permit escape of hot gases from the refrigerant receiver 1. Correspondingly, when the power element 17 is cooled the material 20 will begin to solidify and shrink in volume. As the material 20 shrinks in volume, the spring 26 will move the pistons 11 and 22 inward thus closing the valve 9 against its port. When the valve 9 is closed, further inward movement of the piston 11 is prevented but the lost-motion spring 24 will cause the piston 22 and plug member 21 to be moved further inward with further shrinkage of the material 20 upon cooling and solidification so that voids will not be formed in the solidified material 20. To accomplish the foregoing described operation the spring 24 must be sufficiently strong to compress the thermostatic material 20 back into the power element 17 upon cooling but must be weaker than the spring 26 so that the piston 22 may have its initial movement without moving the valve 9 away from its seat.

One of the principal advantages of a valve of this type is that the valve will not begin to open until a certain predetermined temperature is reached and the valve will then open rapidly to full open position within a small range of tem-

perature. Correspondingly, the valve will close rapidly upon fall of temperature within a narrow temperature range thus preventing loss of fluid through the valve by "bleeding" as in conventional thermostatically operated valves when they begin to open.

In Fig. 2 there is shown a valve similar to that described which is adapted for use in automatically draining hot water tanks upon excessive rise in temperature. In domestic hot water heaters which are provided with a heating coil within the furnace, there is no means to control the amount of hot water produced with the result that in very cold weather when the furnace is operated to produce large quantities of heat, there will be produced an excess of hot water which may reach a dangerous condition. To remedy this situation it is customary in cold weather to draw off quantities of hot water to prevent overheating of the domestic water supply.

The valve shown in Fig. 2 is provided to automatically drain water from a domestic hot water tank upon excessive rise of temperature. The parts in Fig. 2 which are common to those in Fig. 1 are given similar reference characters. There is shown in Fig. 2 a fragmentary section of a hot water tank 27 which has a screw-threaded fitting 2 thereon in which is screw-threadedly secured a plug member 3. The plug member 3 has a large bore 28 at one end and has a bore 29 extending longitudinally through the body portion thereof. There is a tubular guide member having a cup-shaped member 13 which is screw-threadedly secured in the bore 28 of the plug member 3 and which has a cylindrical projecting portion 14 extending from the base portion thereof. The projecting portion 14 has a passageway or bore extending longitudinally therethrough and provides a valve port 29^a opening into the cup-shaped portion 13. There are provided one or more apertures 30 in the wall of the cylindrical projecting portion 14 to permit flow of liquid to the valve port 29^a. There is a valve member 31 which has a valve stem 32 extending into the bore of the cylindrical projecting portion 14 and adjustably screw-threadedly secured in an actuating piston 33. The pistons 33 and 22 comprise a plunger or thrust member similar to the arrangement shown in Fig. 1. The valve member 31 is cooperable with the valve port 29^a and operable to control flow of liquid through the valve port 29^a. The valve member 31 has a cylindrical projecting portion or flange 34 extending longitudinally therefrom providing a cup-shaped portion. There is provided a spring 23 which seats at one end against the end wall 35 of the large bore 28 and at its other end within the cylindrical flange portion 34 of the valve member 28 and which is operable to urge the valve member 31 toward closed position. The power element and thermo-expansive material is substantially identical in structure to that shown in Fig. 1.

The operation of this valve is substantially identical to that for Fig. 1. The essential advantages of this valve as previously described are that the valve will not begin to open until a predetermined temperature is reached and then it will open rapidly to full open position within a very small predetermined range of temperature.

Having thus described the invention what is claimed and is desired to be secured by Letters Patent of the United States is:

1. A thermostatic valve comprising a plug closure member for a threaded aperture and hav-

ing a passageway therethrough including an enlarged internally threaded portion, said closure member having an externally screw-threaded portion, a tubular guide member extending from said closure member concentric with said threaded portions, said guide member having an enlarged end portion threadedly secured in said threaded passageway portion and forming therewith a chamber and having apertures for flow through said passageway, valve means having a piston reciprocally guided in said guide member and having a valve member, a valve seat having a valve port open to said passageway and receiving said valve member for controlling flow therethrough, a coil spring in said chamber and held under compression against said valve means to urge said valve member against said seat, a thermostatic power element carried by said guide member and containing a thermostatic material having a low rate of expansion both below and above a predetermined temperature range, a second motion transmitting piston arranged to be actuated by said power element and spaced from and engageable with said first-named piston upon predetermined expansion of said thermostatic material, and a second spring operable with said second piston and operable to return the same to its initial position spaced from said first-named piston upon contraction of said thermostatic material.

2. A thermostatic valve comprising a plug member having a passageway therethrough and having a portion forming a valve port, a valve member cooperable with said valve port and operable to control flow through said passageway, a valve stem for said valve member, a thermostatic power element having a movable piston spaced from said valve stem and engageable therewith upon predetermined increase in temperature to move said valve member toward open position, said power element containing a thermo-responsive material having a low rate of expansion both below and above a predetermined temperature range and having a high rate of expansion within said predetermined temperature range, a first spring interposed between said piston and said valve stem, a second spring positioned within said plug member and cooperable with said valve member and operable to resist movement of said valve member toward open position, said first spring being compressible to the extent of expansion of said thermo-responsive material at temperatures below said predetermined range to permit engagement of said piston and said valve stem, said second spring being of sufficient strength to prevent said valve member from being moved toward open position by said power element prior to engagement of said piston and said valve stem, and said first spring being of sufficient strength to return said piston to its initial position spaced from said valve stem upon contraction of said thermo-responsive material.

3. A thermostatic valve comprising a plug member externally screw-threaded at one end for insertion in the wall of a fluid container, a passageway extending longitudinally through said plug member, a partition in said passageway and having an aperture forming a valve port, a valve positioned on the outer side of said partition and cooperable with said valve port to control flow therethrough, a valve stem secured to said valve and extending through said valve port, a cup-shaped member-screw threadedly secured in said passageway inward from said partition, said cup-shaped member having at least one aperture

in its base for passage of fluid to said valve port and having a hollow cylindrical projection extending from the central portion of its base, said projection having an annular flange at its end portion, a cup-shaped power element secured to said flange and closing the hollow opening from said projection, a flexible diaphragm extending across said power element and secured between said power element and said flange, a thermo-responsive material enclosed by said power element and said diaphragm, said thermo-responsive material having a low rate of expansion both below and above a predetermined temperature range and having a high rate of expansion within said temperature range, a compressible elastic plug positioned within said hollow projection and abutting said diaphragm, lost motion means positioned within said projection and abutting said elastic plug, a piston in said hollow projection abutting said last-motion means and extending into the passageway portion closed by said cup-shaped member, said piston having an annular flange around its end portion and having a central passage in which is secured said valve stem, a helical spring positioned between said piston flange and said partition and operable to urge said valve toward closed position, and said spring and said lost-motion means being operable to prevent said valve from being opened by said power element at temperatures below said predetermined temperature range.

4. A thermostatic valve comprising a plug member externally screw-threaded at one end portion for insertion in the wall of a fluid container, said plug member having a large bore at the other end portion thereof and having a small bore extending longitudinally therethrough, a cup-shaped member having its open end portion screw-threadedly secured in said large bore and having a cylindrical projection extending from its base, a cylindrical passageway extending from said cup-shaped member through said cylindrical projection and forming a valve port at said cup-shaped member, at least one aperture in the wall of said cylindrical projection for passage of fluid to said valve port, a valve member positioned externally of said port and having a valve stem extending into said passageway, said valve member having a hollow cylindrical flange portion extending longitudinally therefrom, a spring positioned against said valve member within said cylindrical flange portion and against said plug member at the end wall of said large bore, said spring being operable to urge said valve member toward closed position, a piston slidably positioned in said passageway and screw-threadedly secured to said valve stem, said cylindrical projection having an annular flange around its end portion, a hollow cup-shaped power element having a flange portion securing it to said projection flange and closing said passageway, a flexible diaphragm closing the open end of said power element and secured at its edge portion between said power element and said projection flange, a thermo-responsive material enclosed by said power element and said diaphragm, said material having a low rate of expansion both below and above a predetermined temperature range and having a high rate of expansion within said temperature range, an elastic compressible plug member positioned in said passageway between said diaphragm and said piston, compressible lost-motion means positioned in said passageway between said plug member and said piston and compressible to the extent of expansion of said

thermo-responsive material at temperatures below said predetermined range, and said spring and said lost-motion means being operable to prevent opening movement of said valve member by temperature response of said power element at temperatures below said predetermined range.

5. A thermostatic actuating device comprising a tubular member, a cup-shaped power element casing closing one end of said tubular member, a thermostatic material within said casing, said material having a high rate of expansion within a predetermined temperature range, a flexible diaphragm separating said casing from the bore of said tubular member and movable in response to the expansion of said thermostatic material, an elastic plug member positioned in the bore of said tubular member and movable by said diaphragm, an actuating piston slidably positioned in the bore of said tubular member and operable to be moved by said plug member, an operating piston engaging said plug member and spaced a predetermined distance from said actuating piston, a lost-motion spring positioned between said pistons and operable to permit lost-motion between said pistons at temperatures below said predetermined temperature range, said operating piston being operable upon movement by said plug member first to compress said lost motion spring and second to engage and move said actuating piston, a second spring engaging said actuating piston and restraining movement of the same during the lost motion movement of said operating piston, and said lost motion spring being operable to move said operating piston to its initial position spaced from said actuating piston upon contraction of said thermostatic material.

6. A thermostatic valve comprising a plug member externally screw-threaded at one end for insertion in the wall of a fluid container, a passageway extending longitudinally through said plug member, a partition in said passageway and having an aperture forming a valve port, a valve positioned on the outer side of said partition and cooperable with said valve port to control flow therethrough, a valve stem secured to said valve and extending through said valve port, a cup-shaped member screw-threadedly secured in said passageway inward from said partition, said cup-shaped member having at least one aperture in its base for passage of fluid to said valve port and having a hollow cylindrical projection extending from the central portion of its base, said projection having an annular flange at its end portion, a cup-shaped power element secured to said flange and closing the hollow opening from said projection, a flexible diaphragm extending across said power element and secured between said power element and said flange, a thermo-responsive material enclosed by said power element and said diaphragm, said thermo-responsive material having a low rate of expansion both below and above a predetermined temperature range and having a high rate of expansion within said temperature range, a compressible elastic plug positioned within said hollow projection and abutting said diaphragm, a first piston positioned within said projection and abutting said elastic plug, a second piston in said hollow projection and extending into the passageway portion closed by said cup-shaped member, said pistons being normally separated by a distance equal to the amount of expansion of said thermostatic material at temperatures below said predetermined temperature range, a lost-motion spring compres-

70 sively positioned between said pistons, said second piston having an annular flange around its end portion and having a central passage in which is secured said valve stem, a helical spring positioned between said piston flange and said partition and operable to urge said valve toward closed position, and said springs being operable to prevent said valve from being opened by said power element at temperatures below said predetermined temperature range.

7. A thermostatic valve comprising a plug member externally screw-threaded at one end portion for insertion in the wall of a fluid container, said plug member having a large bore at the other end portion thereof and having a small bore extending longitudinally therethrough, a cup-shaped member having its open end portion screw-threadedly secured in said large bore and having a cylindrical projection extending from its base, a cylindrical passageway extending from said cup-shaped member through said cylindrical projection and forming a valve port at said cup-shaped member, at least one aperture in the wall of said cylindrical projection for passage of fluid to said valve port, a valve member positioned externally of said port and having a valve stem extending into said passageway, said valve member having a hollow cylindrical flange portion extending longitudinally therefrom, a spring positioned against said valve member within said cylindrical flange portion and against said plug member at the end wall of said large bore, said spring being operable to urge said valve member toward closed position, a piston slidably positioned in said passageway and screw-threadedly secured to said valve stem, said cylindrical projection having an annular flange around its end portion, a hollow cup-shaped power element having a flange portion securing it to said projection flange and closing said passageway, a flexible diaphragm closing the open end of said power element and secured at its edge portion between said power element and said projection flange, a thermo-responsive material enclosed by said power element and said diaphragm, said material having a low rate of expansion both below and above a predetermined temperature range and having a high rate of expansion within said temperature range, an elastic compressible plug member positioned in said passageway between said diaphragm and said piston, a second piston in said passageway and abutting said plug member, said second piston having a projection extending toward and spaced from said first-named piston, a lost-motion spring compressively positioned between said pistons, and said springs being operable to prevent opening movement of said valve member by temperature response of said power element at temperatures below said predetermined range.
